By his Attorney:

John E. Earle

United States Patent Office.

WILLIAM A. IVES, OF NEW HAVEN, CONNECTICUT.

Letters Patent No. 106,168, dated August 9, 1870.

IMPROVEMENT IN BUNG-BORER.

The Schedule referred to in these Letters Patent and making part of the same.

To all whom it may concern:

Be it known that I, WILLIAM A. IVES, of New Haven, in the county of New Haven and State of Connecticut, have invented a new Improvement in Bung-Borers; and I do hereby declare the following, when taken in connection with the accompanying drawing and the letters of reference marked thereon, to be a full, clear, and exact description of the same, and which said drawing constitutes part of this specification, and represents in—

Figure 1, a side view, looking toward the cutting-edge;

Figure 2, a side view turned one-fourth around.

Figure 3, a sectional view through the throat; and in Figure 4, a transverse section on line *x x*.

This invention relates to an improvement in the article of manufacture known as "bung-borers," the object being to produce a cheap and durable steel borer, provided with a gimlet point; and

It consists in a thin or sheet-metal pod, of conical form, the two edges of sheet metal brought nearly together, the one a cutting salient edge, and the space between the two edges forming the throat, the point threaded, so as to form a screw or gimlet point, and combined with a cast-metal head, to which the pod is riveted or otherwise secured.

A is the pod or body of the borer, formed from thin

steel or sheet metal, the two edges brought nearly together, as seen in fig. 4, the one, *a*, being a salient cutting-edge, the other serving as a gauge to govern the thickness of cut, while the whole body serves as a guide; and, running to a point, *d*, it is threaded, so as to make what is known as a gimlet point.

The pod thus formed is secured to a head, *B*, the said head being fitted to receive the pod, and the two joined together by rivets or otherwise, as seen in fig. 3.

The head is cast with openings, *d*, through which to clear the pod, and with a socket, *f*, for the handle.

This construction produces a cheap steel borer, the gimlet point aiding in the feeding of the borer, while its form insures a perfectly round and smooth hole.

The head of cast metal is easily and cheaply formed, and may, if desirable, be made from malleable iron.

I claim as my invention—

As an improved article of manufacture, the herein-described "bung-borer," consisting of the conical body *a*, formed in the manner described, provided with a gimlet point, *d*, and combined with a cast-metal head, *B*, in the manner substantially as set forth.

W. A. IVES.
